UNITED STATES PATENT OFFICE.

FRANK L. CUPPLES, OF NATICK, MASSACHUSETTS.

BAG HOLDER.

Application filed September 12, 1922. Serial No. 587,651.

To all whom it may concern:

Be it known that I, FRANK L. CUPPLES, a citizen of the United States, residing at Natick, in the county of Middlesex and 5 State of Massachusetts, have invented new and useful Improvements in Bag Holders, of which the following is a specification.

The invention relates to a bag-holder adapted to be mounted on a support suitably elevated above a floor, and to support 10 a net bag in position to receive articles to be confined in said bag while being washed.

The object is to provide a bag-holder adapted to be operatively mounted on variously formed supports, constituting portions of the equipment of a laundry.

The invention is embodied in a bag-holder which includes an open frame and bag-engaging jaws carried thereby, the frame being adapted to be operatively and removably mounted on a support, which may be the mouth of a relatively large laundry basket, or may be otherwise provided, and adapted also to be fixed to a support provided by the top of a laundry assorting and bagging table.

Of the accompanying drawings forming a part of this specification,—

Figure 1 is a top plan view of a bag-holder embodying the invention.

Figure 2 is a section on line 2—2 of Figure 1, and shows the holder removably mounted on a laundry basket.

Figure 3 is a section on line 3—3 of Figure 1.

Figure 4 is a bottom plan view.

Figures 5 and 6 are perspective views showing the jaws detached from the frame.

Figure 7 is a top plan view, showing a portion of the top of a laundry table, and a bag-holder secured to said top.

The same reference characters indicate the same parts in all of the figures.

In the drawings, 12 represents a rectangular frame, preferably oblong, and preferably composed of wooden bars or members suitably united at the corners of the frame. Two opposite members of the frame are provided with longitudinal guides, which are preferably grooves 13, formed in the inner sides of said members.

14 represents a bag-engaging jaw fixed to a member of the frame, at one end of the opening bounded by the frame, and projecting above the upper side of the frame.

15 represents a movable bag-engaging

jaw, also projecting above the upper side of the frame, and provided with runners 16, slidably engaged with said guides, the runners being preferably elongated metal strips, riveted to the jaw 15, and adapted to slide in the grooves 13.

Each of said jaws is preferably formed from a single piece of sheet or plate metal, such as steel. The jaw 14 includes an upright body portion 14^a, and a flange 14^b, bent from said portion and extended from the opposite ends thereof, to form bag-engaging ears 14^c, the body portion being attached, as by screws 18, to one of the frame members. The jaw 15 includes an upright body portion 15^a, and a flange 15^b, bent from said portion and extended from the opposite ends thereof to form bag-engaging ears 15^c. The strips forming the runners 16 have bent end portions connected, as by screws or rivets 19, with the body portion 15^a.

The jaws and portions of the frame surround an opening formed to receive a bag 20, engaged with the jaws, the bag depending from the frame when the latter is operatively supported above a floor. The frame is adapted to be loosely and removably mounted on a support, which may be the 25 mouth of a laundry basket 21, resting on a floor, the basket being oblong, and the frame resting on two opposite edges of the basket mouth, so that the bag depends into the basket. The only function of the basket thus employed is to operatively support the frame and permit the charging of the bag. To prevent endwise displacement of the frame on the basket, I provide stop members 22 and 23, projecting downwardly 30 from the under side of the frame, at one end thereof, and adapted to engage a portion of the basket 21, as indicated by Figure 2. It is obvious that the frame may rest loosely on any other suitable support sufficiently elevated above a floor.

As shown by Figure 7, the frame may be secured, as by screws 24, to the top 25 of a laundry assorting and bagging table, said top being provided with a recess or opening 26, formed to receive the frame, the upper surface of the latter being preferably flush with the upper surfaces of the top 25.

The frame being mounted on a support as described, the operator moves the jaw 110 35 toward the fixed jaw 14, until the jaws are spaced a minimum distance apart. The

bag is then engaged with the jaws and caused to depend through the opening in the frame. The movable jaw is then moved away from the fixed jaw until the mouth of the bag is sufficiently opened.

The frictional engagement between the runners and the guides holds the movable jaw in bag-opening position. When the bag has been charged, the movable jaw is moved toward the fixed jaw to permit the removal of the bag.

The frame and the jaws constitute a bag-holding appliance, adapted to cooperate either with a basket-shaped support, on the mouth of which the frame is loosely deposited, or with a support formed as a table, the top of which has an opening wherein the frame is secured, the frame being maintainable in a horizontal position on the support, with the jaws projecting above the frame, for the convenient engagement of a bag therewith. When the frame cooperates with either form of support, a bag engaged with the jaws depends through the frame opening, and is held in position for convenient filling.

The movable jaw, the fixed jaw, and portions of the side members of the frame surround a variable bag-receiving space between the end portions of the frame. Said end portions project in opposite directions from said space, so that the frame may be operatively supported at both end portions, to prevent a bag depending through said space from tipping the frame. When the frame is portable and the appliance is adapted to be supported by a laundry basket, the stops 22 and 23 at one end portion of the frame, engage one of the edges of the basket mouth, while the opposite end portion of the frame bears loosely on the opposite edge of said mouth. As shown by Figure 4, the stop 22 is elongated, and extends entirely across the frame, while the stops 23, which are spaced apart, are located at opposite edges of the frame, and collectively constitute the equivalent of an elongated stop extending entirely across the frame. The elongation of said stops prevents horizontal endwise movements and horizontal swinging movements of the frame on the basket mouth.

I claim:

1. A bag holder consisting of a readily portable rectangular frame, a relatively stationary bag engaging jaw having a section secured to one of the end members of the frame and extending upward therefrom, the upper end of said jaw being deflected laterally and projecting over the upper surface of the end frame member to which the jaw

is attached, and a second, relatively movable, jaw connected by tongue and groove joints with the side members of the frame so that it may be moved longitudinally 65 thereof and projecting above the upper surface of the frame, the upper end of said jaw being deflected in a direction opposite that in which the deflected section of the stationary jaw extends, the frame being distinct and complete in itself and adapted to freely rest on a support.

2. A bag holder consisting of a rectangular frame distinct and complete in itself, a relatively stationary bag engaging jaw secured to the inner face of an end member of the frame and extending above the upper surface of the frame, the portion of said jaw above the frame being deflected laterally and projecting over the upper face of the 80 end frame member to which the jaw is secured, a second, relatively movable, jaw having a portion extending between the side members of the frame and projecting above the frame, the portion of said jaw above the 85 frame being deflected laterally in a direction opposite that in which the deflected portion of the stationary jaw extends, the deflected portions of both jaws being of greater length than the distance 90 between the side members of the frame so that the ends thereof project over the side members of the frame, and means connecting the portion of the relatively movable jaw between the side members of the 95 frame with said members and permitting movement of the jaw longitudinally of the frame, said frame being adapted to freely rest on a support.

3. A bag holder consisting of a rectangular frame distinct and complete in itself, adapted to be supported in a horizontal position and having one element of a tongue and groove connection on each side member, a relatively stationary bag engaging jaw attached to an end member of the frame and extending above the upper surface of said member, the upper end of said jaw being deflected laterally in a direction toward the outer vertical face of the end member, and a relatively movable jaw provided with means cooperating with the tongue and groove connection elements of the side members of the frame, so that the jaw may be moved longitudinally of the frame, and having a portion extending above the frame with its upper end deflected laterally in a direction opposite that of the deflected section of the stationary jaw.

In testimony whereof I have affixed my 120 signature.

FRANK L. CUPPLES.
